COLLAPSIBLE SHIPPING CONTAINER

Howard L. Smith, Lexington, Ky.

Application May 14, 1931. Serial No. 537,456

13 Claims. (Cl. 217—43)

This invention relates to a collapsible shipping container and has for its primary object to provide, in a manner as hereinafter set forth, an article of such class which may be folded in a compact bundle for return shipping, thereby encouraging the reuse of shipping containers and consequently tending to conserve timber.

A further object of the invention is to provide a container of the character aforesaid which may be made in a variety of shapes as occasion may require for such uses as poultry coops, egg crates, fruit crates, hogsheads and the like, and which includes an even number of side wall sections locked together and further locked as a unit to a top section and a bottom section.

A further object of the invention is to provide a container of the character aforesaid which may be replaced by sections in the event of damage or loss of any part of the container.

With the foregoing and other objects in view, the invention consists of the novel construction, combination and arrangement of parts as herein-after more particularly described, and as illustrated in the accompanying drawings wherein is shown an embodiment of the invention, but it is to be understood that the drawings and the description are to be considered as illustrative rather than limitative.

In the accompanying drawings in which like numerals are employed to designate like parts throughout the several views:

Figure 1 is a perspective of a container in accordance with this invention.

Figure 2 is a bottom plan thereof.

Figure 3 is a vertical section therethrough taken substantially on the line indicated at 3—3 of Figure 1.

Figure 4 is a horizontal section taken substantially on the line indicated at 4—4 in Figure 3.

Figure 5 is a vertical section taken substantially on the line indicated at 5—5 in Figure 3.

Figure 6 is a bottom plan of the top section.

Figure 7 is a fragmentary vertical section taken substantially on the line indicated at 7—7 in Figure 1.

Figure 8 is a fragmentary perspective of a side wall section.

Figure 9 is a fragmentary perspective of another side wall section adapted to be interlocked with respect to the section shown in Figure 8.

Figure 10 is a fragmentary perspective of the top section.

Figure 11 is a reduced elevation of the side wall section shown in Figure 9.

Figure 12 is a plan of the container showing the

parts thereof in knockdown relation for return shipping.

Referring to the drawings in detail wherein by way of example is shown a container of rectangular construction, the numeral 1 indicates a pair of side wall sections which are alternately arranged and locked with respect to another pair of side wall sections 2, the sections 1 and 2 being locked as a unit with respect to a top section 3 and a bottom section 4.

The bottom section 4 as shown is of rectangular construction, formed of wood or metal and provided on its lower face and adjacent its ends with a pair of transversely extending reinforcing strips

5. Midway between the ends thereof, the section 4 is provided on its lower face with a similar reinforcing strip 6. In spaced relation to each end of each of the strips 5 and 6 is an opening 7 which extends therethrough and into the bottom section 4.

Each of the side wall sections 1 as shown is in the form of a rectangle, formed of wood or metal, and provided adjacent the ends with an upright reinforcing member, post or corner piece 8 consisting of a pair of angularly disposed parts 80

9 and 10. The lower ends of the parts 9 and 10 are bent inwardly in overlapping relation as indicated at 11 for supporting the bottom section 4 at the corners of the latter. The part 9 is rigidly connected with the section 1 in a manner 85

to space the part 10 from the end face of the section 1. The parts 9 and 10 are arranged with their upper edges flush with the upper edge of the section 1, the part 9 being provided with an

ear 12 extending across the upper face of the section 1 and rigidly secured thereto. In spaced relation to the upper edge thereof, the part 10 is formed with a slot 13. In spaced relation to the top and bottom of the member 8, the latter is formed at the line of joinder of the parts 9 90

and 10 with a pair of lugs 14 which are pressed inwardly and which are severed from the parts 9 and 10 at the upper and lower edges of the lugs. The inwardly extending lower end portions 11 of the parts 9 and 10 are formed with openings 15 95

which are adapted to be brought into registry with the openings 7 in the reinforcing strips 5 of the bottom section 4. Midway between the ends of each side wall section 1 is an upright reinforcing strip 16 which is rigidly secured to the outer 105

face of the section. The strip 16 has its upper end 17 projected above the upper edge of the section and is provided in its projecting portion with a transverse opening 18. The lower end of the strip 16 is bent inwardly as indicated at 19 110

and is formed with an opening 20 which is adapted to be brought into registry with one of the openings 7 in the strip 6 of the bottom section 4.

Each of the side wall sections 2 as shown is of rectangular construction, formed of wood or metal, and provided at its sides, adjacent the bottom thereof and in spaced relation to the top thereof, with recesses 21. Secured to the outer face of the section 2 are a pair of horizontally disposed reinforcing strips 22, one of which has its upper edge flush with the upper edge of the section, and the other of which has its lower edge arranged in spaced relation to the lower edge of the section. At the ends thereof, the strips 22 are formed with depending tongues 23 which project downwardly into the recesses 21 in spaced relation to the side walls of the latter.

The top section 3 includes a pair of complementary parts 24 which are of rectangular construction as shown, and preferably formed of wood. The parts 24 are provided on their lower faces with hinges 25 connecting them together, and are provided on their upper faces with a reinforcing strip 26 which is rigidly secured to one of the parts 24 and which extends across the hinge line between the parts 24. The end portions 27 of the strips 26 project beyond the sides of the sections 3 and are provided with slots 28 for the reception therethrough of the end portions 17 of the strips 16 when the container is assembled. Extending transversely across the lower face of each part 24, adjacent the outer edge of the latter, is a reinforcing strip 29 which is provided with a pair of longitudinally extending tongues 30. The tongues 30 of the strips 29 are for insertion through the slots 13 in the parts 10 of the upright members 8.

When the parts of the container are assembled, the bottom section 4 is supported by the lower end portions 11 of the upright members 8 and by the lower end portions 19 of the strips 16. The portions 19 of the strips 16 are secured with respect to the strip 6 by means of suitable studs 31 extending through the aligned openings 20 and 7 in the portions 19 and strip 6 respectively. In large containers, similar studs preferably will be inserted through the aligned openings 15 and 17 in the portions 11 and strips 5 respectively, although these latter studs may be omitted if desired. The side wall sections 2 are locked with respect to the sections 1 by the extension of the tongues 23 through the lugs 14 pressed from the uprights 8. The top section 3 is locked with respect to the side wall sections 1 by the insertion of the tongues 30 through the slots 13, and by the insertion of the end portions 17 of the strips 16 through the slots 28 in the strip 26. Suitable keepers, such as 32, may be extended through the openings 18 to prevent displacement of the strip 26 with respect to the strips 16. The end portions of the top section 3 extend across the upper edges of the side wall sections 2 to prevent removal of the tongues 23 with respect to the lugs 14.

It will be seen from reference to Figure 12 that the upright members 8 may be disposed with such members of one of the sections 1 in abutting relation with respect to such members of the other section 1 for embracing the sections 2, 3 and 4 when the container is knocked down for return shipping.

Although the container herein illustrated and described is of rectangular construction, it is to be understood that the container may be of any other shape wherein the side walls of the con-

tainer are divisible by two, such as a hexagon or octagon. Likewise the container may be of circular construction by forming the side walls of the container of an even number of segments.

What I claim is:—

1. A shipping container comprising, a first set of side wall sections, angular upright posts at the side edges of and of greater height than said wall sections, a second set of side wall sections alternately arranged with respect to the wall sections of the first named set, means for latching the side edges of said second set to said posts, a bottom section, projections on the wall sections of said first set for supporting the bottom section, a top section, and spaced means extended from each end of said top section and through said posts for detachably latching the former to the latter.

2. A shipping container comprising, a first set of side wall sections, angular upright posts at the side edges of said sections, said posts being formed with slots, a second set of side wall sections alternately arranged with respect to the wall section of the first named set, means for latching the side edges of the wall sections of said second set to said posts, a bottom section, upright strips on the wall sections of said first set, projections of said strips for supporting the bottom section, a centrally hinged top section, tongues projecting from the peripheral face of the top section on opposite sides of the hinge therefor and extending through said slots in said posts, a rigid strip extending across the hinge line of the top section, and means for securing said rigid strip to said upright strips.

3. A knockdown shipping container comprising, a first set of side wall sections, angle-shaped corner pieces, each having one of its flanges secured to and extending laterally from an end of a wall section of said set, a bottom supported by said corner pieces, a second set of side wall sections, said corner pieces and wall sections of the second set having coacting means for releasably connecting the wall sections of the two sets of wall sections together, said corner pieces being of greater height than said wall sections, a top for seating upon a wall section of each of said sets, and means extended from each end of said top and through one of the flanges of each of said corner pieces for latching the latter to said top.

4. A knockdown shipping container comprising, a first set of side wall sections, angle-shaped corner pieces, each having one of its flanges secured to and extending laterally from an end of a wall section of said set, a bottom supported by said corner pieces, a second set of side wall sections, said corner pieces and wall sections of the second set having coacting means for releasably connecting the wall sections of the two sets of wall sections together, a top, said corner pieces and top having coacting means for releasably connecting the top to the wall sections of the two sets of wall sections, a bracing means encompassing the wall sections of the first mentioned set, the said bottom and top, and means for detachably connecting that part of the bracing means for said top to the parts of the bracing means for the wall sections of the first mentioned set.

5. A knockdown shipping container comprising, a first set of side wall sections, angle-shaped corner pieces, each having one of its flanges secured to and extending laterally from an end of a wall section of said set, a bottom supported by said

- corner pieces, a second set of side wall sections, said corner pieces and wall sections of the second set having coacting means for releasably connecting the wall sections of the two sets of wall sections together, a top, said corner pieces and top having coacting means for releasably connecting the top to the wall sections of the two sets of wall sections, a bracing means encompassing the wall sections of the first mentioned set, the said bottom and top, means for detachably connecting that part of the bracing means for said top to the parts of the bracing means for the wall sections of the first mentioned set, and said top formed of a pair of hinged sections shiftable inwardly upon the pivot of the hinged means therefor that portion of the bracing means for the top arresting the outward shifting of the sections of the top.

6. A knockdown shipping container comprising, a first set of side wall sections, angle-shaped corner pieces, each having one of its flanges secured to and extending laterally from an end of a wall section of said set, a bottom supported by said corner pieces, a second set of side wall sections, said corner pieces and wall sections of the second set having coacting superposed means for releasably connecting the wall sections of the two sets of wall sections together, said corner pieces being of greater height than said wall sections, a top, and spaced means extended from each end of the top and extending through the corner pieces in proximity to the upper ends of the latter for latching the top to the wall sections of the two sets of wall sections.

7. A knockdown shipping container comprising a first set of side wall sections, a second set of side wall sections, corner pieces formed of a pair of flanges disposed at right angles to each other, said corner pieces having inwardly extending portions to provide supports, a bottom mounted upon said supports, said corner pieces secured to the ends of the wall sections of the first mentioned set and extended laterally from such ends, said corner pieces having inwardly extending coupling means at the points of joinder of the flanges thereof, the wall sections of said second set of wall sections having means coacting with said coupling means for releasably connecting the wall sections of said two sets of wall sections together, and corner pieces being of greater height than said wall sections, the wall sections of the second set being of less height than the wall sections of the first set, a top arranged between the wall sections of the first set and over the wall sections of the second set, and means carried at each end of said top and extending between the latter and the wall sections of the second set and through the corner pieces for releasably connecting the top of the wall sections of the said sets.

8. In a knockdown shipping container, two opposed pair of angle-shaped corner pieces, each corner piece being formed of a pair of flanges disposed at right angles to each other, opposed side wall sections, each side wall section being secured to one of the flanges of a pair of flanges of a corner piece of each pair of corner pieces, the flanges secured to said wall sections extending laterally from the ends of the latter, said flanges having inherent portions thereof extending inwardly to provide coupling means, a bottom supported by said corner pieces, opposed side wall sections positioned between said secured flanges, opposing said non-secured flanges and having means coacting with said

coupling means for releasably connecting the first mentioned opposed side wall sections together, a top, and means secured to the top, extending from each end of the latter and through the non-secured flanges of the corner pieces for detachably connecting the top with the several wall sections.

9. In a knockdown shipping container, two opposed pair of angle-shaped corner pieces, each corner piece being formed of a pair of flanges disposed at right angles to each other, opposed side wall sections, each side wall section being secured to one of the flanges of a pair of flanges of a corner piece of each pair of corner pieces, the flanges secured to said wall sections extending laterally from the ends of the latter, said flanges having inherent portions thereof extending inwardly to provide coupling means, a bottom supported by said corner pieces, opposed side wall sections positioned between said secured flanges, opposing said non-secured flanges and having means coacting with said coupling means for releasably connecting the first mentioned opposed side wall sections together, a top, means secured to the top, extending from each end of the latter and through the non-secured flanges for detachably connecting the top with the several wall sections, an exteriorly arranged sectional bracing means for the container when set up, and means for releasably connecting the sections of the bracing means together.

10. In a knockdown shipping container, angle-shaped corner pieces having inwardly extending portions to provide supports, a bottom for mounting on said supports, a first set of side wall sections for positioning on said supports to abut opposed edges of said bottom, a second set of side wall sections for positioning on said supports to abut opposed edges of said bottom, said corner pieces being secured to the ends of the wall sections of the first named set of side wall sections, extending laterally from said ends and for opposing the wall sections of the second named set of side wall sections, a top for positioning between the wall sections of the first named set of side wall sections and for seating upon the wall sections of the second named set of side wall sections, said corner pieces and wall sections of the second named set of side wall sections having coacting means for detachably connecting the side wall sections of said first and second named sets of side wall sections together, and means secured to the top, extending from each end of the latter and through the corner pieces for detachably connecting the top with the said several wall sections.

11. In a knockdown shipping container, angle-shaped corner pieces having inwardly extending portions to provide supports, a bottom for mounting on said supports, a first set of side wall sections for positioning on said supports to abut opposed edges of said bottom, a second set of side wall sections for positioning on said supports to abut opposed edges of said bottom, said corner pieces being secured to the ends of the wall sections of the first named set of side wall sections, extending laterally from said ends and for opposing the wall sections of the second named set of side wall sections, a top for positioning between the wall sections of the first named set of side wall sections and for seating upon the wall sections of the second named set of side wall sections, said corner pieces and wall sections of the second named set of side wall sections having coacting means for detachably connecting the side wall sections of the first and second named sets of side wall sections together, and means secured to the top, extending from each end of the latter and through the corner pieces for detachably connecting the top with the said several wall sections.

gether the side wall sections of the first and second named sets of side wall sections, said corner pieces and top having coacting means for detachably connecting said top with the side wall 5 sections of said first and second named sets of side wall sections together, exteriorly arranged bracing means for the side wall sections of the first named set of side wall sections and said bottom, exteriorly arranged bracing means for said 10 top, and means for detachably connecting the bracing means for the side wall sections of the first named set of side wall sections to the bracing means for the top.

12. A shipping container comprising, a first set of side wall sections, angle shaped corner pieces extending from the wall sections of said set and provided with inwardly disposed lugs, a second set of side wall sections, the side wall sections of said second set being alternately arranged with respect to the side wall sections of said first set, tongues carried by the side wall sections of said second set and extending through said lugs for detachably connecting the side wall sections of said first set to the side wall sections of said second set, a top section, a bottom section, and means extending from each end of said
